UNITED STATES PATENT OFFICE

2,422,234

METHOD AND APPARATUS FOR PRODUCING
TUBULAR FABRIC

Maurice A. Goldman, New Brunswick, N. J., assignor to Fibre Products Laboratories, Inc., New Brunswick, N. J., a corporation of New Jersey

Application October 14, 1943, Serial No. 506,235

23 Claims. (Cl. 154—1)

1

The present invention relates to a method of and apparatus for producing tubular fabric adapted for various uses; and more particularly to provide porous axially-compressible cores or tubes for supporting dye-cops, for example, cop-tubes of the type illustrated and described in my prior copending application for United States Letters Patent Serial No. 443,155, filed May 15, 1942, entitled Cop-tube or yarn-support, now Patent No. 2,336,086, dated December 7, 1943.

One of the objects of the present invention is to provide a method of and apparatus for producing a tubular fabric having crossing strands of fibrous material bonded together at their intersections.

Another object is to provide a method of and apparatus for producing a self-supporting tubular fabric from flexible textile material.

Another object is to provide a method of and apparatus for bonding the crossing strands by impregnating one or more of the strands with a plastic.

Another object is to provide a method of and apparatus for producing a self-supporting tubular fabric by impregnating one of the crossing strands with a plastic and treating the plastic to make the impregnated strand relatively rigid and resistant to deformation.

Another object is to provide a method of and apparatus for producing a tubular fabric of the type indicated by supporting a plurality of strands of textile material spaced around a common axis, winding a strip impregnated with a plastic about the plurality of strands and treating the plastic to cause it to bond the strip to the strands at their intersections and render the impregnated strip relatively rigid and resistant to collapse or deformation.

Another object is to provide an apparatus of the type indicated comprising a supporting mandrel for receiving the strands disposed in crossing relationship and means for impregnating one of the strands with a plastic.

Another object is to provide an apparatus of the type indicated having means for guiding a plurality of warp strands lengthwise of the periphery of the mandrel and means for winding a filling strip helically about the warp strands.

Another object is to provide an apparatus of the type indicated with means for curing and setting the plastic after the strands are arranged in crossing relationship on the mandrel.

Another object is to provide an apparatus of the type indicated with means for advancing the fabric along the mandrel and feeding it off from the end thereof.

Another object is to provide an apparatus of the type indicated with means for controlling the pitch of the coils of the helically-wound filling strip.

2

Another object is to provide an apparatus of the type indicated which is adapted to operate at high speed to continuously produce tubular fabric.

Another object is to provide an apparatus of the type indicated with means for severing predetermined lengths of the tubular fabric to provide cores or tubes for supporting dye-cops of textile yarn.

10 Another object is to provide an apparatus of the type indicated which is of comparatively simple and compact construction, fully automatic in operation, and adapted for use over long periods of time without repair or replacement of its parts.

15 Further objects of the invention are set forth in the following specification which describes the method of producing the fabric and a preferred form of construction of the apparatus, by way of example, as illustrated by the accompanying drawings. In the drawings:

Fig. 1 is a plan view of the main elements of an apparatus incorporating the novel features of the present invention and showing a plurality of warp strands as being fed lengthwise of a cylindrical mandrel with a filling strip being wound helically about the warp strands;

Fig. 2 is a side elevational view looking in the direction indicated by the arrow 2 in Fig. 1 and showing the means for feeding the filling strip and treating it with a plastic;

Fig. 3 is a side elevational view of the apparatus showing the common driving means for the mandrel and the plurality of feeding heads for advancing the fabric and controlling the pitch of the coils of the helically-wound filling strip;

Fig. 4 is an enlarged longitudinal sectional view of the forward portion of the first feeding head showing two of a plurality of feeding units in the head and illustrating each unit as comprising a pair of longitudinally-spaced feed-wheels for engaging the coils of the helically-wound filling strip;

Fig. 4-a is an enlarged view of the rearward portion of the first feeding head showing the change-gear transmission adapted for varying the speed of rotation of the feed-wheels of the plurality of units;

Fig. 5 is a sectional plan view on line 5—5 of Fig. 4 showing the transmission gearing employed with each head or unit for simultaneously rotating the feed-wheels of the pairs at different speeds;

Fig. 6 is a transverse sectional view on line 6—6 of Fig. 4 showing the arrangement of the forward feed-wheels of the head which surround the mandrel;

Fig. 7 is a transverse sectional view on line 7—7 of Fig. 4 showing the rearward feed-wheels of the head and their mounting in the head;

Fig. 8 is an end view of one of the feeding heads showing the change-gear transmission for rotating the feed-wheels at maximum speed;

Fig. 9 is a view similar to Fig. 8 showing the change-gears arranged for rotating the feed-wheels at an intermediate speed and indicating the manner in which the gears may be adjusted to drive the feed-wheels at slow speed;

Fig. 10 is an elevational view of the rearward end of the apparatus showing the means for intermittently severing predetermined lengths of the tubular fabric as it is fed from the mandrel;

Fig. 11 is a sectional view on line 11-11 of Fig. 3 showing the keys on the slotted frame for connecting it to the forward end of the mandrel and the circular comb for guiding the warp strands; and

Fig. 12 is a diagrammatic view illustrating the manner in which the coils of the helically-wound filling strip are advanced by the feed-wheels in the different heads.

The method of the present invention consists in disposing a plurality of strands of suitable material in crossing relationship around a common axis and bonding the crossing strands at their intersections to produce a continuous tubular fabric. The step of arranging the plurality of strands in crossing relationship may be accomplished by winding the strands helically in opposite directions circumferentially of a fixed mandrel or by feeding either a single filling strip or a plurality of strips around a plurality of warp strands extending lengthwise of the periphery of a rotating mandrel. Preferably a plurality of warp strands are guided to extend longitudinally in spaced, parallel relationship surrounding the periphery of the mandrel and a single filling strip of the material is wound helically about the warp strands to cause it to cross them at a predetermined angle. By varying the pitch of the helical coils of the winding strip or by changing the direction in which the warp strands are guided along the periphery of the mandrel any desired angle of the crossing strands may be obtained.

While any suitable material may be used for the warp strands and filling strip, with the particular tubular fabric herein illustrated and described both the strands and the strip preferably are composed of textile material. The warp strands may comprise roving of textile material such as cotton having a slack-twist to give it the necessary strength. Other fibrous materials may be used, however, and the method of the present invention further contemplates the use of warp strands in the form of a knitted, braided or woven sleeve or stockinette about which the filling strip is wound. The filling strip may be either in the form of a sliver or slack-twist roving of textile material such as cotton to render it extremely permeable by a plastic in a liquid state, yet provide the necessary strength to adapt it to be wound about the warp strands.

The filling strip preferably is impregnated and coated with a resin or plastic before it is wound about the warp strands on the mandrel. When the strip is in the form of a sliver it is twisted after impregnation and wound on a take-off spool while wet. The impregnated and twisted sliver is thereafter immersed in a bath of the plastic as it feeds toward the mandrel. Preferably, the filling strip is in the form of a slack-twist roving and it may be given several immersions in the plastic to insure thorough impregnation. It is to be understood, however, that

the strip may be composed of other materials besides textiles or composed of other types of filaments such as flax, hemp, or synthetic materials such as rayon or nylon and may have any degree of twist so long as it is capable of being readily impregnated with a plastic. The plastic may be of any hard setting type capable of being treated to cause it to set rapidly. A phenol formaldehyde resin, known by the trade name "Bakelite," in a water phase is particularly well adapted for such use as it may be caused to set by merely extracting the water. The setting of the plastic may be accelerated by any suitable treatment such as passing it through a drying oven or ovens when Bakelite in a water phase is used. Preferably, the strip of slack-twist cotton roving is immersed in successive baths of liquid Bakelite or a similar plastic and then passed through a preheating oven to render the plastic sticky or tacky before it is wound about the warp threads.

As the impregnated strip is wound helically about the warp strands extending longitudinally of the mandrel the tacky plastic migrates to the warp strands at the intersections to assist in the bonding action at the intersections. The warp strands and filling strip are continuously advanced along the mandrel and passed through drying ovens to cause the plastic to cure and set whereby to bond the strip to the strands at their intersections, thus forming a tubular fabric. The setting of the plastic also makes the helical filling strand relatively rigid and resistant to deformation and radial compression. During the winding of the strip and the setting of the plastic to produce the tubular fabric the latter is continuously advanced and the rate of advance is positively controlled to maintain a predetermined constant pitch between the coils of the helical strip in the finished article.

The tubular fabric of crossing strands bonded together at their intersections may be slit longitudinally and folded flat for any use to which such sheet fabrics are commonly used; for example, as the mat or base for linoleum, or for bags, screens, wall-lath, camouflage and the like. In the specific embodiment of the invention as herein illustrated and described the method is directed more particularly to the production of porous, self-supporting and axially-compressible tubes or cores such as illustrated in my copending application for letters patent for Cop-tube or yarn-support, referred to above. In accordance with the present method, sections of the fabric of proper length for utilization as cop-tubes are severed from the continuous tubular fabric as it is fed off from the rearward end of the mandrel.

When yarn is to be dyed by the "Franklin process," so called, the material is wound upon a sleeve or stockinette of fabric supported by an axially-compressible metal core or spring to provide a porous cop or package. A plurality of such dye-cops are mounted in series on a supporting stringer and compressed axially so that the ends of adjacent cops abut and the yarn throughout the length of the stringer will have substantially the same density and permeability. Several stringers are mounted in a suitable kier or vat and the dye-liquor or other treating fluid is circulated radially through the yarn, either outwardly from the stringer to the kier or inwardly from the kier to the stringer. Such a dye-cop and method of dyeing are illustrated and described in United States Letters Patent No. 996,761, to J. C. Hebden

5

et al., issued July 4, 1911. The metal cores or helical springs used in the Franklin process of dyeing are expensive, usually being constructed of stainless steel to resist oxidation and prevent discoloration of the yarn. After being dyed the yarn is generally rewound on a paper or other inexpensive core for shipping, or in some cases, the dyed packages may be shipped on the metal cores and the latter returned to the dye house after the yarn has been unwound therefrom. Due to the weight and bulk of the metal cores, however, the cost of transportation of the dyed yarn and the expense of returning the tubes usually exceeds the cost of rewinding the yarn and this type of core has other disadvantages, for example loss of its use during trans-shipment.

Cores or tubes made in accordance with the present invention will perform all the functions of the metal spring cores heretofore used in the art and may be manufactured at low cost so that they may be discarded after a single use if desired. Usually the cost of the cores made by the method and apparatus of the present invention is less than the cost of rewinding the yarn, or the cost of transportation and return of the metal cores to the dye-house. For these reasons the cop-tubes of the present invention are more economical to use than the metal cores, eliminating the expense of rewinding the yarn or trans-shipment of the metal cores with the extra handling involved.

The present drawings illustrate a preferred form of apparatus for carrying out the steps of the method. Referring to Figs. 1 and 3, the apparatus comprises a horizontal mandrel 2 having a floating support in heads 3, 4 and 5 mounted on the upper ends of pedestals 6. The rearward end of the mandrel 2 projects into the open end of a slotted frame 7 and its forward end extends beyond the head 5. Ribs 8 on the frame 7 project into slots 9 in the end of the mandrel 2 with their ends serving as keys to connect the mandrel and frame for rotation as a unit, see Fig. 11. A shaft 10 is fixedly attached to the end of the frame 7 opposite from the mandrel 2, being journaled in spaced bearings 11 supported at the upper end of a pedestal 12. Mounted fast on the shaft 10 between the bearings 11 is a sprocket-wheel 13 which is driven from a drive-shaft 14 by a chain 15. The drive-shaft 14 is journaled in bearings in the pedestals 6 and 12 below the mandrel 2 and extends parallel thereto throughout the entire length of the latter. The drive-shaft 14 is driven by a suitable prime mover 16, herein illustrated as an electric motor, through a reduction gearing unit 17 and a chain 18 connecting sprockets 19 and 20 on the unit and shaft, respectively. The axially-aligned mandrel 2, frame 7 and shaft 10 thus are adapted to be continuously rotated as a unit by the electric motor 16.

Mounted to rotate in the slotted frame 7 are suitable spools 22, each carrying a plurality of strands S of fibrous material such as slack-twist roving wound thereon. To facilitate replenishment of the strands S the spools 22 are mounted to rotate on a removable spindle 23 extending between the sides of the frame 7. The strands S are herein considered as in the nature of warp ends, being adapted to be drawn off from the spools 22 between the ribs 8 of the frame 7 to extend longitudinally in spaced relationship around the periphery of the mandrel 2. Preferably, the strands S are guided between the teeth of a suitable circular comb 24, see Figs. 3 and 11, to position them in spaced parallel relationship

75

6

as they are drawn off from the spools 22. The strands S may feed in parallel relationship helically around the periphery of the mandrel 2 at any desired angle of lead, but in the embodiment of the invention as herein illustrated they are guided to feed in parallel relation to the axis of the mandrel. In either case the strands extend longitudinally of the mandrel 2 intervening between its periphery and the heads 3, 4 and 5, later to be described in detail.

Adjacent one side of the mandrel 2 means are provided for feeding a strip T of fibrous material, such as cotton sliver or roving, to cause it to be coiled about the warp strands S as the mandrel 2 rotates, see Fig. 1. As explained above, a cotton sliver may be impregnated with the plastic and thereafter twisted and wound on a supply spool 27 while wet. In the preferred form of construction illustrated in Figs. 1 and 2, the strip T in the form of a slack-twist roving is wound on the spool 27 and impregnated and coated with the plastic as it feeds therefrom to the mandrel 2. The spool 27 is mounted to rotate in a suitable frame 28 and the strip T is drawn off from the spool and directed by suitable guides 29, 30 and 31 through a trough 34 containing the liquid resin or plastic to cause it to be impregnated therewith as it is fed between suitable nip-rolls 35. The strip T may be immersed as many times as is necessary to thoroughly impregnate it with the plastic and, as illustrated in Fig. 2, the strip is directed by similar guides 29, 30 and 31 to cause it to be immersed successively in the plastic in two additional troughs 36 and 37 and to be squeezed between the nip-rolls 38 and 39 to remove surplus plastic therefrom.

The impregnated strip T then is guided to a reel 41 to wind a plurality of turns of the material thereon and from the reel the strip is guided to the periphery of the mandrel 2. The reel 41 is carried by an axial shaft 42 mounted to rotate in spaced bearings 43, being enclosed in an oven 44 having an electrical heating unit 45 of suitable construction therein. Preferably, the oven 44 has openings 46 adjacent the bottom of its side walls and vent openings 47 in its top to permit circulation of the air therethrough. The temperature of the oven 44 and the number of coils of the impregnated strip T on the reel 41 are so controlled as to render the plastic sticky or tacky when the strip leaves the reel 41 and is wound around the warp strands S on the rotating mandrel 2.

The nip-rolls 35, 38 and 39 and the reel 41 are rotated by any suitable driving means to advance the strip T at a linear speed proportionate to the peripheral speed of the mandrel 2. As illustrated in Figs. 1 and 2, the reel-shaft 42 has a worm-wheel 48 mounted fast thereon which meshes with a worm 49 on a shaft 50 driven from the drive-shaft 14 by bevel gearing shown at 51 in Fig. 2. A pulley 52 at the opposite end of the reel-shaft 42 drives a belt 53 which, in turn, drives pulleys 54 on the drive-shafts for the several sets of nip-rolls 35, 38 and 39. Between the pulleys 54 of the adjacent sets of nip-rolls 35, 38 and 39 idler pulleys 55 are provided. The belt 53 is also guided by a pulley 56 and a spring-pressed idler-pulley 57. It will be apparent that with the proper ratio between the worm-wheel and worm 48, 49 and pulleys 52, 54 the reel 41 and nip-rolls 35, 38, 39 can be driven at the required rate of speed to feed the strip T at a linear speed corresponding to the peripheral speed of the mandrel 2.

The heads 3, 4 and 5 are provided with operating mechanism enclosed therein for advancing the filling strip T and warp strands S lengthwise of the mandrel 2 at a predetermined controlled rate of speed so that the filling strip is coiled about the warp strands in a continuous helix. Between the heads 3, 4 and 5 are drying ovens 58 and 59 of any suitable type which act to accelerate the curing and setting of the plastic carried by the impregnated strip by evaporating the moisture therefrom.

The operating mechanism in each of the heads 3, 4 and 5 is adapted to engage and positively advance the coils of the strip T as they are wound about the warp strands S and the operating means in the different heads cooperate to maintain the coils compressed in an axial direction between the heads 3 and 4 while the plastic is being cured, and finally to extend or more widely space them between the heads 4 and 5 while the plastic is being set. All the heads 3, 4 and 5 are of similar construction, each comprising a stationary annular housing 60 and a rotatable element 61 mounted therein surrounding the mandrel 2, see Figs. 4, 4-a and 6. The stationary housing 60 may comprise annular sections 64, 65 and 66 connected by screws 67 and 68 and the section 66 has a reduced tubular extension 69 and a depending base 70 which seats on and is secured to the top of its respective pedestal 6.

The rotatable element 61 is in the form of a sleeve mounted for rotation on spaced roller bearings 71 and 72 in the tubular extension 69 of the housing 60 with a radial flange or disk 73 at its inner end for rotation in the housing proper. The inner race of the roller bearing 71 seats against an annular shoulder 76 on the sleeve of the rotatable element 61 and the outer race abuts against a shoulder 77 on the reduced extension 69 of the housing 60, see Fig. 4. A thrust ring 78 fastened to the end of the tubular extension 69 of the housing 60 engages against the end of the outer race of the bearing 72, see Fig. 4-a, and the bearings are held in spaced relationship by rings 79 and 80 extending between their inner and outer races. The sleeve portion of the rotatable element 61 projects outwardly beyond the tubular extension 69 of the housing 60 and mounts a sprocket-wheel 81 and gear 82. The sprocket 81 and gear 82 are keyed or otherwise secured to the sleeve portion of the rotatable element 61 and are held against axial movement thereon by a ring 83 attached to the end of the sleeve with the hub of the sprocket abutting the end of the inner race of the bearing 72. A chain 84 connects the sprocket 81 with a sprocket 85 on the drive-shaft 14, see Fig. 3, to continuously drive the rotatable element 61 in synchronism with the mandrel 2.

Enclosed within the head 3 are a plurality of feed units A, B, C and D mounted on the radial flange 73 of the rotatable element 61 in angular spaced relationship around the periphery of the mandrel 2, see Fig. 6. Each feed unit A, B, C and D comprises a pair of feed-wheels 88 and 89, see Fig. 4, arranged with their axes spaced longitudinally of the mandrel 2 and adapted for cooperation with its periphery.

The feed-wheel 88 of each unit is of composite construction comprising axially-spaced sections 90 and 91, see Fig. 7, provided with radially-projecting teeth or cogs 92 on their peripheries terminating in a contour conforming to the cylindrical periphery of the mandrel 2. The teeth 92 on the wheel 88 of each feed unit A, B, C 75 to a shaft 128 journaled in the bearings in the

and D are adapted to engage the coils of the strip T wound on the mandrel 2 to feed them longitudinally thereof as the wheels rotate. The pitch or distance between adjacent teeth 92 on the wheels 88 corresponds to the pitch or distance between adjacent coils of the strip T as it winds onto the mandrel 2 and by constructing each wheel in two sections 90 and 91 each coil will be engaged at eight points spaced around the periphery of the mandrel as shown in Fig. 6 to determine its position thereon. Between the sections 90 and 91 of the feed-wheels 88 of each unit A, B, C and D is a spur-gear 93 of less diameter than that of the wheel and the wheel-sections and gear are connected by pins 94 and screws 95, see Fig. 7, to cause them to rotate as a unit.

The wheel 88 and gear 93 assembly of each unit A, B, C and D is mounted to rotate on a pin or shaft 96 extending between the sides of a pair of spaced brackets 97 and 98 attached to the radial flange 73 of the rotatable element 61. The brackets 97 and 98 for the several feeding units are of identical construction but of opposite hand and each bracket has a supporting flange 99 abutting the face of the radial flange 73 on the element 61 and an offset flange 100 at its outer end overlying the end thereof, see Figs. 4 and 5. The brackets 97 and 98 are attached to the flange 73 by means of screws 101 and 102. Preferably, a spacing tie-rod 103 extending between the wheels 88 and 89 connects the brackets 97 and 98, thus acting as a brace therebetween. The outer free ends of the brackets 97 and 98 of the plurality of units A, B, C and D are preferably connected to a ring 105 by means of screws 106, see Fig. 4, to reinforce the structure.

As shown in detail in Fig. 7, the pin or shaft 40 96 mounting the feed-wheel 88 and gear 93 assembly extends through bushings 108 and 109 mounted in elongate slots 110 in the brackets 97 and 98, the bushings being urged to slide in a direction toward the center of the head 3 under the compression of coil springs 111. The spring 111 for each bushing 108 or 109 surrounds the shank of a screw 112 which is inserted through a hole in one end of the bracket 97 or 98, holes in the bushing 108 or 109 and pin 96 and screwed into a lug 107 on the bracket. The spring 111 acts between one side of the bushing and an adjustable nut 113 on the threaded portion of the screw 112, see Fig. 7. The nut 113 may be turned on the threaded portion of the screw 112 to adjust the tension of the spring 111 and then locked in adjusted position by a locknut 114.

The feed-wheel 88 of each unit A, B, C and D is driven by a gear 118, see Figs. 4 and 7, mounted to rotate on a pin or shaft 119 extending between the spaced brackets 97 and 98 in parallel relation to the shaft 96. The shaft 119 extends through bushings 120 and 121 mounted to slide in slots 122 in the brackets 97 and 98. Straps 123 and 124 at the outer sides of the brackets 97 and 98, see Figs. 4 and 7, connect the ends of the shafts 96 and 119 to adapt the wheel 88 and gears 93 and 118 for movement as a unit radially of the head 3. As shown in Fig. 7 the shafts 96 and 119 are held against axial movement by cotter pins 125 extending through their ends and the bushings 108, 109 and 120, 121 are held in their spaced relation to the sides of the wheel 88 and gear 118 by collars 126. As shown in Figs. 4 and 5 the gear 118 is driven by a gear 127 keyed to a shaft 128 journaled in the bearings in the

brackets 97 and 98 and the arcuate slots 122 in the brackets are concentric to the axis of the shaft to permit the gear 118 to swing around the gear 127 when the wheel 88 moves radially toward or away from the periphery of the mandrel 2.

The feed-wheel 89 of each unit A, B, C and D also is of two-part construction and mounts a gear 130 between its sections similar to the wheel 88. The feed-wheel 89 is provided with more teeth 131 on its periphery than the wheel 88 to compensate for a reduction in pitch between its teeth corresponding to the reduced pitch of the coils of the strip T between the wheels 88 and 89, see Fig. 4. Each wheel 89 is mounted to rotate on a shaft 132 extending between the spaced brackets 97 and 98. The gear 130 is driven through a compound gear 133 mounted on a shaft 134 and the shafts 132 and 134 are connected by straps 135 for movement as a unit in slots 136 and 137 in the brackets 97 and 98 under the action of springs 111 which are arranged to operate in the manner as previously described with reference to the wheel 88. Compound gear 133 is driven from a gear 138 keyed to the shaft 128 at the side of the gear 127, see Figs. 5 and 6, through the gears 139 and 140 to drive the feed-wheel 89 at a slower rate of speed than that of the wheel 88. The gears 139 and 140 are mounted on shafts 141 and 142 extending between the spaced brackets 97 and 98 and the arrangement is such that change-gears may be substituted in the train to drive the feed-wheel 89 at any desired speed ratio with respect to the wheel 88 corresponding to the number of teeth 131 and 92 on the respective wheels. As illustrated in Fig. 5, collars 143 fast on the shaft 128 and shafts 141 and 142 hold them against axial movement in the brackets 97 and 98.

Mounted for rotation in the housing 60 of the head 3 is a ring-gear 144 having external spur-teeth 146 and internal worm-teeth 145, see Figs. 4 and 6. The worm-teeth 145 of the ring-gear 144 mesh with the teeth of the gears 127 of the several units A, B, C and D. It will be noted that the gears 127 of the plurality of units A, B, C and D mesh with the worm-teeth 145 at points spaced 90° apart so that each tooth 92 and 131 on the feed-wheels 88 and 89 driven from the gears 127 will be in advance of the corresponding tooth on the preceding feed-wheel a distance equal to a quarter of the pitch between teeth due to the increasing lead of the worm whereby the teeth on the wheels will engage each coil in the helix of the strip T. Attached to the opposite sides of the ring-gear 144 are bifurcated brackets 147 mounting anti-friction rollers 148, see Figs. 4 and 6. The rollers 148 bear against annular shoulders 149 and 150 on the housing 60 at opposite sides of the ring-gear 144 to restrain the latter from lateral displacement. Also carried by the ring-gear 144 are anti-friction rollers 151, see Fig. 4, mounted on studs 152 between the brackets 147. The rollers 151 roll on an annular race 153 on the interior of the cylindrical wall of the housing 60 to mount the ring-gear for rotation.

The ring-gear 144 is adapted to be rotated by driving means comprising a shaft 154 journaled in suitable bearings 155 and 156 in the base 70 of the housing 60 and a bracket 157 attached to the side of the base, see Figs. 4 and 4-a. Mounted on the forward end of the shaft 154 is a gear 158 having teeth in mesh with the external spur-teeth 146 on the ring-gear 144. Splined

to the shaft 154 adjacent its opposite end is a sleeve 159 formed with a grooved collar 161 and carrying a clutch-member 160 keyed to the sleeve. A shifting fork 162 is mounted fast on a rock-shaft 163 which also carries a hand-lever 164 fast thereon. The shifting fork 162 is slotted at its ends for engaging trunnions 172 projecting from the side of a ring 173 in the groove of the collar 161, see Fig. 8. Loosely mounted on the shaft 154 adjacent the sleeve 159 is a driving member 165, see Fig. 4-a, formed with a conical clutch-face 166 for cooperation with the clutch-member 160 on the sleeve and carrying a sprocket-wheel 167. The driving member 165 is adapted to be driven continuously from an auxiliary motor 168, see Fig. 3, by a chain 169 connecting its sprocket-wheel 167 to a sprocket-wheel 170 on the motor shaft. The driving member 165 and sleeve 159 are normally held in axially-spaced relationship by a spring 171, shown in Fig. 4-a, but the sleeve may be slid axially by the shifting fork 162 to engage the clutch-member 160 with the driving member. Such engagement of the clutch elements is for the purpose of rotating the ring-gear 144 and driving the feed-wheels 88 and 89 under manual control while the rotating element 61 of the head 3 is idle during the initial operation of advancing the coils of the filling strip to feed the warp strands into the head.

A gear 174 keyed to the sleeve 159 meshes with a compound gear 175, see Figs. 4-a and 8, mounted to rotate on a stud 176 projecting from the base 70 of the housing 60. Mounted to rock on the stud 176 is a pair of triangularly-shaped plates 177 and 178 carrying a stud 179 for mounting a compound gear 180 therebetween. One element of the compound gear 180 meshes with the gear 175. The plates 177 and 178 carry a stud 181 mounting a reversing gear 182. As illustrated in Fig. 8, the plates 177 and 178 are provided with aligned holes 184, 185 and 186 which overlie quadrants 187 having tapped holes 188, 189 and 190. Screws 191 are adapted to be inserted in the holes 184, 185 and 186 and screwed into any one of the three tapped holes 188, 189 and 190 to lock the rockable plates 177 and 178 in any one of three positions of adjustment. When the rockable plates 177 and 178 are locked in the neutral or inoperative position illustrated by full lines in Fig. 9 by inserting screws 191 through the holes 184, 185 and 186 in the plates and screwing them into the intermediate holes 189 in the quadrants 187, the shaft 154 is disconnected from any driving means. Preferably, the shaft 154 is positively locked against rotation when the plates 177 and 178 are adjusted to neutral position by means of a member 192 having gear-teeth engageable with the teeth on one element of the compound gear 180 and clamped in fixed position by a screw 193 whereby to hold the ring-gear 144 against rotation, see Fig. 9.

By removing the screws 191 and rocking the plates 177 and 178 in counterclockwise direction to the position illustrated in Fig. 8 one element of the compound gear 180 is brought into meshing engagement with the gear 82 on the sleeve of the rotatable element 61 of the head 3, see Fig. 4-a. The ring-gear 144 will then be rotated by the shaft 154 to give an added increment of rotative movement to the feed-wheels 88 and 89.

When the plates 177 and 178 are rocked in clockwise direction to the position indicated by dot-and-dash lines in Fig. 9 the gear 182 is brought into meshing engagement with the gear

11

82 on the sleeve of the rotatable element 61. The shaft 154 and ring-gear 144 then will be rotated in the opposite direction from that with the previously-described arrangement whereby to cause the feed-wheels 88 and 89 to be rotated with a reduced increment of movement. It will be understood that gears 115 and 180 are adapted to be changed for others of different size to give any particular speed ratio desired.

The head 4 is of a construction identical with that described with reference to the head 3 but arranged in reversed relationship so that the feed-wheels 89 of each unit A, B, C and D first will engage the coils of the helically-wound strip T to feed them into the head and the feed-wheels 88 will engage the coils to feed them out from the head so as to maintain the coils in extended relationship on the mandrel 2 while the plastic is becoming hardened or set, see Fig. 12.

The head 5 has the same construction and arrangement of parts as the head 4 except that each of the several units A, B, C and D is provided with the feed-wheels 88 alone. Consequently, the coils of the strip T are maintained in their extended relationship by the feed-wheels 88 from the time they leave the head 4 until they are discharged from the rearward end of the mandrel 2.

As illustrated in Figs. 1 and 10, a reciprocating cutter 200 is provided at the rearward end of the mandrel 2 for severing units of predetermined length from the continuous tubular fabric as it is fed from the mandrel 2. The cutter 200 may be of any suitable type, and is herein illustrated as in the form of a rotary disk with a sharpened peripheral edge and mounted at the end of a shaft 201 journaled in bearings 202 on a slidable carriage 203. The cutter 200 is continuously rotated at high speed from an electric motor 204 through the means of a belt 205 connecting pulleys 206 and 207 on the motor and shaft 201. The carriage 203 is mounted to slide in guide-ways 208 on a table 209 and has a lug 210 depending through a suitable slot in the table, see Fig. 10. The carriage 203 is adapted to be actuated in timed relation to the rotation of the mandrel 2 by a lever 211 pivoted intermediate its ends and having a fork 212 at one end engaging a pin 213 in the depending lug 210. The opposite end of the lever 211 carries a follower 214 engaging the periphery of a cam 216 having a lobe 217 and a dwell-portion 218 each of which extends through approximately 180° of its circumference. A spring 219 connected between the lever 211 and table 209 acts to slide the carriage in one direction and maintain the follower 214 in engagement with the periphery of the cam 216.

The cam 216 is mounted fast on a shaft 220 which is driven from the drive-shaft 14 through reduction gearing to actuate the carriage 203 in the proper timed relation to the rotation of the mandrel 2. The reduction gearing comprises intermeshing bevel gears 222 and 223 on the drive-shaft 14 and a shaft 224 suitably journaled in a bearing on the table 209. A worm 225 on the shaft 224 meshes with a worm-wheel 226 mounted on the cam-shaft 220 to continuously rotate the cam 216 at a relatively slow rate of speed. One embodiment of the apparatus having been described in detail its mode of operation is explained as follows:

The apparatus is prepared for operation by drawing off strands S from the spools 22 which rotate on the spindle 23 in the open or slotted frame 7. The strands S are positioned between 75

12

the teeth of the circular comb or guide 24, see Fig. 11, and then drawn forwardly between the ribs 8 to extend along the periphery of the mandrel 2. The filling strip T is drawn off from the supply spool 27, see Figs. 1 and 3, carried around the guides 29, 30 and 31 and through the nip-rolls 35, 38 and 39 to cause it to feed through the liquid plastic in the successive troughs 34, 36 and 37. Several turns of the strip T impregnated with the liquid plastic are then wound around the reel 41 and the end of the strip extending therefrom is attached to the strands S on the mandrel 2.

To initially feed the filling strip T through the heads 3, 4 and 5 the mandrel 2 is turned manually to cause the strip to wind around the warp strands S. Simultaneously the warp strands S are slid forwardly along the mandrel to engage the first few coils of the filling strip T with the teeth 92 of the feed-wheels 88 of the units A, B, C and D in the head 3. After the leading coils of filling strip T are advanced to a position to be engaged by the teeth 92 of the feed-wheels 88 the hand-lever 164 is actuated manually, see Fig. 4-a, to rock the shifting fork 162 and slide the sleeve 159 axially to engage its clutch-member 160 with the clutch-face 166 on the driving member 165. The driving member 165 driven by the motor 168 through the chain 169 then will rotate the sleeve 159 and shaft 154 splined thereto. The gear 158 at the end of the shaft 154 in mesh with the spur-teeth 146 on the ring-gear 144 will rotate the latter relatively of the feed-units A, B, C and D in the head 3, see Fig. 4. Such rotation of the ring-gear 144 will cause the worm-teeth 145 on its interior to drive the gears 127 of the units A, B, C and D in mesh therewith which, in turn, will drive the gears 118 and 93 to rotate the feed-wheels 88. Upon rotation of the feed-wheels 88 their teeth 92 will engage the leading coils of the strip T and advance them along the mandrel 2 toward the feed-wheels 89. The operation of winding the strip T around the warp-strands S is continued until the leading coils of the wound strip T are engaged by the feed-wheels 89 in the head 3.

Preferably, the coils of filling strip T are compacted slightly or closed together between the feed-wheels 88 and 89 by rotating the wheel 88 at a faster rate than that of the wheel 89. This causes the warp strands S to be undulated or "puckered" between adjacent coils, see Fig. 12, the longitudinally-extending strands remaining in this condition whereby to prevent slippage of the coils relatively of the warp strands as the tubular fabric is delivered from the machine. Furthermore, the closing of the coils of the strip T and the undulation of the wrap strands S tend to loosen the coils on the mandrel 2 and increase the area of contact of the strip with the strands. The feed-wheels 89 of the several units A, B, C and D are also driven from the gear 127 on the shaft 128 through the gears 138, 139, 140, 133 and 130 to advance the coils of the strip T along the mandrel 2. The feed-wheels 89 of the units A, B, C and D are driven at a slower rate of speed than the feed-wheels 88 but are provided with a greater number of teeth corresponding to the lesser pitch of the compacted coils of the strip T. Therefore, the wheels 88 and 89 in the head 3 will operate to advance the coils of the strip T along the mandrel 2 by feeding them both in and out of the head 3 at a constant rate while at the same time cooperating to control their spacing as indicated in Fig. 12.

The warp strands S and filling strip T will be

advanced along the mandrel 2 and fed through the heads 4 and 5 in the manner explained with reference to the head 3. It will be noted that when the hand-lever 164 is operated to shift the sleeve 159, as before explained, the gear 174 on the sleeve will be moved therewith but not to a sufficient extent to disengage it from the compound gear 175, see Figs. 4—a and 8. Upon release of the hand-lever 164 at any of the heads 3, 4 and 5 the spring 171 will automatically slide 10 the sleeve 159 on the shaft 154 to release the clutch-face 160 from the clutch-member 166 on the driving member 165. During the manual operation of starting the feeding action in the apparatus the feed-wheels 88 and 89 may be moved away from the periphery of the mandrel 2, but when released they will be pressed yieldingly toward the mandrel by the springs 111. In the head 4, which is of reverse arrangement from that of the head 3, the coils of the filling strip T will be extended to their original pitch or spacing between the feed-wheels 89 and 88 and the feed-wheels in the heads 4 and 5 thus will positively control the pitch of the coils to maintain them in their proper relationship.

After the warp strands S and filling strip T have been initially fed through the heads 3, 4 and 5 the gear-train shown in Fig. 9 may be adjusted to one of its three positions to cause the feed-wheels 88 and 89 of the units A, B, C and D to be driven at the proper speed. For the purpose of illustration let it be assumed that the gear-train is adjusted to the position shown in Fig. 8. The plates 177 and 178 then will be held in position by the screws 191 extending through the holes 184, 185 and 186 and screwed into the tapped holes 188 of the fixed quadrants 187. The gear 180 thus will be meshed with the gear 82 on the sleeve of the rotatable element 61 while the gear 175 is meshed with the gear 174 on the sleeve 159. The apparatus then is ready for automatic operation.

By means of suitable control mechanism the prime-mover 16 may be energized and, operating through the reduction gearing unit 17 and the chain 18 and sprockets 19 and 20, the drive-shaft 14 will be rotated therefrom. The drive-shaft 14, in turn, will rotate the mandrel 2 through the chain 15 and sprocket 13. Simultaneously the rotating elements 61 in the heads 3, 4 and 5 will be driven from the shaft 14 through the chains 84 and sprockets 81 and 85 to rotate in synchronism with the mandrel 2.

Rotation of the mandrel 2 will cause the filling strip T to coil about the warp strands S spaced around its periphery and the rotation of the drive-shaft 14 will be transmitted through the bevel gear unit 51, shaft 50, and worm 49 and wheel 48, see Fig. 2, to rotate the reel 41 at the proper speed to feed the strip to the mandrel. The pulley 52 at the opposite end of the reel-shaft 42 from the worm-wheel 48 will drive the belt 53 which, in turn, will drive the pulleys 54 on the shafts for the nip-rolls 35, 38 and 39 in synchronism with the reel 41. The strip T thus will be drawn off from the supply spool 27 and fed continuously by the nip-rolls 35, 38 and 39 and the reel 41 to avoid excessive strain thereon and thereby prevent rupture of the strand. During the feeding of the strip T it will be directed by the series of guides 29, 30 and 31 to cause it to be immersed in the liquid plastic in the successive troughs 34, 36 and 37 to be thoroughly impregnated with the plastic. The impregnated strip T is passed through the drying oven 44 as it

winds on the reel 41 and a portion of moisture therein will be evaporated therefrom to render the plastic sticky or tacky. A portion of the tacky plastic on the strip T being wound around the warp strands S will migrate to the latter at the intersections, thus tending to bond the coils of the strip to the strands.

Simultaneously with the winding of the strip T the warp strands S and previously-wound coils of the filling strip will be advanced longitudinally of the mandrel 2 by the feed-wheels 88 on the rotating element 61 of the head 3. As the element 61 of the head 3 rotates about its axis the units A, B, C and D will revolve therewith bodily in synchronism with the rotation of the mandrel 2. During the rotation of the units A, B, C and D the gears 127 meshing with the worm-teeth 145 on the interior of the ring-gear 144, see Figs. 4 and 6, will be rotated in counterclockwise direction as viewed in Fig. 4, due to the relative movement between the gears 127 and the ring-gear 144, to thereby rotate the shafts 128 to which the gears are splined. The rotation of the gears 127 will be transmitted through the gears 118 and 93 to rotate the feed-wheels 88 of the units A, B, 25 C and D, see Fig. 4, and the teeth 92 on the wheels will advance the coils of the strip T along the periphery of the mandrel 2. As the coils of the strip T are advanced they will cause the warp strands S to undulate or gather therebetween in the manner indicated in Fig. 12 to give a greater area of contact of the strip with the strands and prevent slippage of the strip with respect to the strands. Due to the slight expansion in the diameter of the coils of the filling strip T due to their being closed together slightly, the strip and strands S will be prevented from binding on the mandrel 2 so as to slide freely therealong.

Rotation of the shafts 128 of the units A, B, C and D in the head 3 also will be transmitted through the gears 138, 139, 140, 133 and 130 to rotate the feed-wheels 89 at a slower rate of speed than that of the gears 88. As before explained, the feed-wheels 89 of the units A, B, C and D have a greater number of teeth 131 than the wheels 88 so that they will feed as many coils of the strip T out of the head 3 as are fed in by the wheels 88, but the coils will have a lesser pitch or closer arrangement in the space between the wheels.

While the rotation of the units A, B, C and D has been explained as being relative to the ring-gear 144 it will be understood that the latter is also driven when the gear-train is adjusted as shown in Fig. 8. The compound gear 180 will be driven by the gear 82 on the sleeve of the rotatable element 61 of the head 3 and through the compound gear 175 will drive the gear 174 on the sleeve 159 splined to the shaft 154. The gear 158 at the end of the shaft 154 meshing with the spur-teeth 146 on the ring-gear 144 will rotate the latter whereby to give an added increment of rotation to the feed-wheels 88 and 89 of the units A, B, C and D. By removing the screws 191 and rocking the plates 177 and 178 to the intermediate or neutral position shown in full lines in Fig. 9 the compound gear 180 will be disconnected from the gear 82 on the sleeve of the rotatable element 61. The ring-gear 144 then will remain stationary to drive the feed-wheels 88 and 89 at an intermediate speed. With this adjustment of the gear-train as shown by full lines in Fig. 9, the gears are locked against turning by meshing the teeth on the member 192 with 70 the teeth of the gear 180 and tightening the screw 75

193. By removing the screws 191 and rocking the plates 177 and 178 to the position indicated by dot-and-dash lines in Fig. 9 the gear 182 will be brought into meshing engagement with the gear 82 on the sleeve of the rotatable element 61. The gear 82 then will drive the gears 182, 180, 175 and 174 to rotate the shaft 154 and ring-gear 144 in the opposite direction from that first described to drive the feed-wheels 88 and 89 of the units A, B, C and D with a reduced increment or at low speed. Thus, the change speed transmission gearing may be adjusted to cause the strip T to wind around the warp strands S with three different degrees of pitch to regulate the spacing of the coils.

As the warp strands S and filling strip T are advanced along the mandrel 2 the coils of the strip are engaged and controlled by the feed-wheels 88 and 89 in the heads 4 and 5 in the manner as previously explained. The coils of the strip T will be expanded axially in the head 4 to their original pitch distance and fed outwardly from the head 4 by the feed-wheels 88. The head 5 is provided with the feed-wheels 88 only which engage and control the feed of the coils of the strip T along the mandrel 2 and cooperate to maintain the coils in their extended relationship.

The feed-wheels 89 in the head 3 act to feed the coils of the strip T therefrom and to the feed-wheels 89 in the head 4 and since both these sets of feed-wheels are driven at the same rate of speed they will maintain the same number of coils in the space therebetween. As the coils of the strip T are initially contracted along the mandrel 2 in the head 3 they will continue to be contracted between the heads 3 and 4 to undulate the warp strands S therebetween as illustrated in Fig. 12. During the advancement of the coils of the filling strip T along the mandrel 2 between the heads 3 and 4 they will pass through the drying oven 58 which accelerates the extraction of moisture from the plastic to cause it to cure and partially bend the filling strip T to the warp strands S.

The feed-wheels 88 of the heads 4 and 5 are rotated at the same rate of speed to maintain the coils of the strip T in the extended relationship in which they are discharged from the head 4, as indicated in Fig. 12. During the advance of the coils of the strip T along the mandrel 2 between the heads 4 and 5 they will pass through the drying oven 59 to further accelerate the extraction of moisture from the plastic to cause it to set to render the strip T relatively stiff to resist deformation. The setting of the plastic in the strip T and that portion which migrates to the warp strands S will positively bond the strands to the strip at the intersections to produce a self-supporting tubular fabric.

During the feeding of the tubular fabric along the mandrel 2 the carriage 203 mounting the cutter 200 is actuated intermittently to sever predetermined lengths of the fabric for use as cop-tubes or for other purposes. The carriage 203 is operated by the drive-shaft 14 driving through the bevel gears 222 and 223, shaft 224, worm 225 and wheel 226 to rotate the shaft 200 at a slow rate of speed. The cam 216 on the shaft 200 engaging the follower 214 on the lever 211 effects oscillation of the latter to reciprocate the carriage 203 on the table 209. During each forward sliding movement of the carriage 203 the cutter 200 while rotated at high speed by the motor 204 will contact the tubular fabric at the end of the mandrel 2 to sever predetermined lengths therefrom. Due to the sharp angle of the cam

216 between its lobe 217 and dwell 218 the carriage will be slid across the path of the tubular fabric at a relatively high rate of speed to quickly sever each length from the tubular fabric. The follower 214 on the lever 211 then will ride on the lobe 217 of the cam 216 for a predetermined interval while another length of the tubular fabric is being fed from the mandrel 2. After the cam 216 has rotated throughout the length of the lobe 217 the spring 219 will rock the lever 211 in clockwise direction to return the carriage 203 to its original position, during which movement the cutter 200 will sever another length from the tubular fabric. Thus the cam 216 and spring 219 are caused to operate the lever 211 and carriage 203 alternately in opposite directions in timed relation to the rotation of the mandrel 2 to cause the knife 200 to sever predetermined lengths from the continuous tubular fabric.

It will be observed from the foregoing specification that the present invention provides a method of and apparatus for producing tubular fabric of crossing strands of textile material bonded together at their intersections. It also will be observed that the invention provides for bonding the crossing strands at their intersections by impregnating one of the strands with a liquid plastic and treating the plastic to cause it to cement the crossing strands together. It further will be observed that the invention provides for feeding the tubular fabric along a supporting mandrel and controlling the coils of at least one of the crossing strands to maintain a predetermined pitch between adjacent coils. It still further will be observed that the invention provides for continuously producing tubular fabric in an apparatus which operates automatically to feed warp strands longitudinally of a central support or mandrel, wind or wrap a filling strip impregnated with a plastic about the warp strands, cure and set the plastic to produce a tubular fabric and sever predetermined lengths from the finished fabric.

While the preferred method and a preferred form of apparatus are illustrated and described herein it is to be understood that modifications may be made in the steps of the method and in the construction of the apparatus without departing from the spirit or scope of the invention. For example, other forms of variable speed drives for rotating the ring-gear, such as variable speed hydraulic transmissions, may be substituted for the change-speed gearing illustrated and described. Therefore, without limiting myself in this respect, I claim:

1. The method of making a porous tubular article of manufacture which comprises supporting a plurality of strands of textile material in the form of a cylinder and extending longitudinally thereof, winding a strip of textile material helically around the cylinder of textile material with the coils spaced apart therealong, while impregnating the strip of textile material with a plastic to cause it to migrate to the cylinder of textile material to bond the strip thereto.

2. The method of making a porous tubular article of manufacture which comprises arranging a series of strands of textile material extending longitudinally in spaced apart relation about a common axis, impregnating a strip of textile material with a plastic, and winding the impregnated strip helically around the strands in spaced apart relationship while the plastic is tacky to cause it to migrate to the strands at the inter-

sections of the strip therewith to bond the strip to the strands.

3. The method of making a porous core or tube for supporting a textile package which comprises arranging a series of strands of textile material in spaced relationship about a common axis and extending longitudinally thereof, impregnating a strip of textile material with a liquid plastic, and winding the impregnated strip helically around the strands, with the coils spaced at a distance apart said plastic of the impregnated strip migrating to the strands at their intersections, and treating the plastic to cause it to bond the strip to the strands at their intersections while rendering the strip relatively stiff yet resilient.

4. The method of making porous cores or tubes for supporting textile packages which comprises arranging a series of strands of flexible material in spaced relationship about a common axis and extending longitudinally thereof, continuously advancing the strands longitudinally, impregnating a strip of flexible material with a plastic, continuously winding the impregnated strip helically around the strands with the coils spaced at a distance apart to cause the plastic to migrate to the strands at the intersections of the strip therewith, treating the impregnated strip to cause it to bond the strip and strands at their intersections and render the strip relatively stiff yet resilient, and cutting lengths from the continuous tubular fabric to produce the finished articles.

5. The method of making porous cores or tubes for supporting textile packages which comprises arranging a series of strands of textile material in spaced relationship about a common axis extending longitudinally thereof, impregnating a strip of textile material with a plastic, continuously winding the impregnated strip around the spaced strands with the coils spaced at a distance apart to cause the plastic to migrate from the strip to the strands at the intersections, continuously advancing the wound coils of the strip and the strands to cause the strip to be wound helically around the strands, treating the plastic to cause the strip to be bonded to the strands and to render the strip relatively stiff yet resilient, and cutting off lengths from the continuous tubular fabric to produce the finished articles.

6. In an apparatus of the type indicated, a cylindrical mandrel held against axial displacement, means for feeding textile material along the mandrel surrounding its periphery in contact therewith and extending longitudinally thereof in spaced-apart relationship, means for winding a strip of textile material around the material surrounding the mandrel with the helical coils spaced at a distance apart, and means for applying an adhesive to the strip to bond it to the textile material around which it is wound.

7. In an apparatus of the type indicated, a cylindrical mandrel held against axial movement, means for feeding textile material along the mandrel surrounding its periphery in contact therewith and extending longitudinally thereof in spaced-apart relationship, means for winding a strip of textile material around the material on the mandrel with the helical coils spaced at a distance apart, means for impregnating the strip with a plastic, and means for treating the plastic to cause it to bond the strip to the material around which it is wound.

8. In an apparatus of the type indicated, a cylindrical mandrel mounted to rotate without

axial displacement, means for rotating the mandrel, means for feeding a plurality of strands of fibrous material surrounding the mandrel in spaced apart relationship extending longitudinally thereof for rotation therewith, means for feeding a strip of fibrous material to the mandrel to cause it to be wound around the plurality of strands with the helical coils spaced at a distance apart, means for advancing the strands and strip lengthwise of the mandrel, and means for applying an adhesive to the strip to bond the crossing strands and strip together at their intersections.

9. In an apparatus of the type indicated, a cylindrical mandrel mounted to rotate without axial displacement, means for rotating the mandrel, means for feeding a plurality of strands of textile material to the mandrel in spaced apart relationship extending longitudinally thereof for rotation therewith, means for feeding a strip of fibrous material to the mandrel to cause it to be wound around the plurality of strands with the helical coils spaced at a distance apart, means for impregnating the strip with a plastic, means for advancing the strands and strip along the mandrel, and means for treating the plastic to cause the strip to be bonded to the strands at their intersections.

10. In an apparatus of the type indicated, a cylindrical mandrel, means for feeding a plurality of strands of textile material longitudinally of the mandrel, means for guiding the strands along the mandrel to maintain them in spaced apart relationship, means for rotating the mandrel and strands, means for feeding a strip of fibrous material to the rotating mandrel to cause it to be wound around the plurality of strands with the helical coils spaced at a distance apart, means for advancing the strands and strip longitudinally of the mandrel, means for impregnating the strip with a plastic to cause it to migrate to the plurality of strands at the intersections, and means for heat treating the plastic to bond the strands together at the intersections to produce a cylindrical fabric surrounding the mandrel.

11. In an apparatus of the type indicated, a cylindrical mandrel, means for feeding a plurality of strands of textile material to the mandrel, means for guiding the strands to dispose them in spaced apart parallel relationship around the mandrel, means for rotating the mandrel and strands, means for feeding a strip of fibrous material to the rotating mandrel to cause it to be wound around the plurality of longitudinally-extending parallel strands with the helical coils spaced at a distance apart, means for advancing the strands and strip longitudinally of the mandrel, means for impregnating the strip with a plastic to cause it to migrate to the plurality of strands at their intersections with the strip, and means for treating the plastic to bond the strip to the strands at the intersections to produce a porous cylindrical fabric surrounding the mandrel.

12. In an apparatus of the type indicated, a cylindrical mandrel, means for feeding a plurality of strands of textile material to the mandrel, means for guiding the strands to dispose them in spaced parallel relationship around the mandrel, means for rotating the mandrel and strands, means for feeding a strip of fibrous material to the rotating mandrel to cause it to be wound helically around the plurality of longitudinally-extending parallel strands with the coils spaced

at a distance apart, means for advancing the strands and strip longitudinally of the mandrel, means for impregnating the strip with a plastic to cause it to migrate to the plurality of strands at their intersections with the strip, and means for heat treating the plastic to bond the strip to the strands at the intersections and render the strip relatively stiff to produce a self-supporting porous tubular fabric on the mandrel.

13. In an apparatus of the type indicated, a cylindrical mandrel, means for rotating the mandrel, means for feeding a plurality of warp strands of textile material extending longitudinally in spaced relationship around the periphery of the mandrel, means for feeding a filling strip of textile material to cause it to be wound around the warp strands with the coils spaced at a distance apart, means for advancing the strands and strip longitudinally of the mandrel, means for impregnating the filling strip with a plastic to cause it to migrate to the warp strands at their intersections with the strip, and means for heat treating the plastic to bond the warp strands and filling strip together at the intersections and render the filling strip relatively stiff whereby to produce a self-supporting porous tubular fabric on the mandrel.

14. In an apparatus of the type indicated, a cylindrical mandrel, means for rotating the mandrel, means for feeding a plurality of warp strands of textile material to the mandrel for rotation therewith, means for guiding the strands in spaced relationship around the periphery of the mandrel extending longitudinally thereof, means for feeding a filling strip of textile material to cause it to wind around the warp strands in helical coils spaced at a distance apart, means for advancing the strip and strands longitudinally of the mandrel, means for impregnating the filling strip with a plastic to cause it to migrate to the warp strands at their intersections with the strip, and means for treating the plastic to bond the warp strands to the filling strip at the intersections and render the strip relatively stiff whereby to produce a self-supporting porous tubular fabric on the mandrel.

15. In an apparatus of the type indicated, a cylindrical mandrel, means for rotating the mandrel, means for feeding a plurality of strands of fibrous material in spaced apart relationship extending longitudinally and distributed circumferentially of the mandrel, means for feeding a strip of fibrous material to the mandrel to cause it to be wound helically around the strands with the coils spaced at a distance apart as the mandrel rotates, means for applying an adhesive to bond the strands to the strip at their intersections therewith, and means engaging between the spaced coils of the strip and continuously advancing them at a constant rate relative to the rotation of the mandrel whereby to cause the strip to be disposed in a helix of predetermined pitch between coils.

16. In an apparatus of the type indicated, a cylindrical mandrel, means for rotating the mandrel, means for feeding a plurality of strands of textile material in spaced apart relationship extending longitudinally and distributed circumferentially of the mandrel, means for feeding a strip of textile material to the mandrel to cause it to be wound around the strands by the rotation of the mandrel with the coils spaced at a distance apart, means for applying an adhesive to bond the strands to the strip at their intersections therewith to produce a porous fabric, and

rotary feed-wheels formed with projections adjacent the periphery of the mandrel for engaging the coils of the strip to advance the fabric along the mandrel and dispose the strip in a helix with a predetermined pitch between coils.

17. In an apparatus of the type indicated, a cylindrical mandrel, means for rotating the mandrel, means for feeding a plurality of strands of textile material in spaced apart relationship extending longitudinally and distributed circumferentially of the mandrel, means for feeding a strip of textile material to the mandrel to cause it to be wound around the strands by the rotation of the mandrel with the coils spaced at a distance apart, means for applying an adhesive to bond the strands to the strip at their intersections therewith to produce a porous fabric, and a plurality of rotary toothed wheels arranged in spaced relationship around the periphery of the mandrel for engaging the coils of the strip as they are wound on the mandrel to advance the fabric therealong.

18. In an apparatus of the type indicated, a mandrel, means for feeding a plurality of strands of textile material in spaced apart relationship extending longitudinally and distributed circumferentially of the mandrel to cause them to cross thereon, at least one of said strands being wound helically on the mandrel with the coils spaced at a distance apart, means for applying an adhesive to bond the crossing strands at their intersections to produce a porous fabric, and separate means rotatable for engaging the wound coils of one of the strands at points spaced longitudinally of the mandrel to shift the coils thereon to regulate their spacing therealong.

19. In an apparatus of the type indicated, a cylindrical mandrel, means for rotating the mandrel, means for feeding a plurality of strands of textile material in spaced apart relationship extending longitudinally and distributed circumferentially of the mandrel, means for feeding a strip of textile material to the mandrel to cause it to be wound around the strands by the rotation of the mandrel with the coils spaced at a distance apart, means for applying an adhesive to bond the strands to their strip at the intersections therewith to produce a porous fabric, and a plurality of sets of feed-wheels spaced longitudinally of the mandrel for engaging the coils to control their spacing therealong.

20. In an apparatus of the type indicated, a mandrel, means for rotating the mandrel, means for feeding flexible textile material in spaced apart relationship extending longitudinally and distributed circumferentially of the mandrel for rotation therewith, means at the side of the mandrel for feeding a strip of fibrous material thereto to cause it to be wound around the textile material in helical coils spaced at a distance apart to produce a porous fabric, means for impregnating the strip with a plastic, means for advancing the fabric along the mandrel, and means adjacent the mandrel for accelerating the setting of the plastic as the fabric advances therealong to render the strip relatively stiff.

21. In an apparatus of the type indicated, a mandrel, means for rotating the mandrel, means for feeding flexible textile material surrounding the mandrel and extending longitudinally thereof for rotation therewith, means at the side of the mandrel for feeding a strip of fibrous material thereto to cause it to be wound around the textile material in helical coils spaced at a distance apart to produce a porous fabric, means

21

for impregnating the strip with a plastic, means for advancing the fabric along the mandrel, and drying ovens enclosing the mandrel for accelerating the setting of the plastic as the fabric is advanced along the mandrel.

22. In an apparatus of the type indicated, a mandrel, means for rotating the mandrel, means for feeding strands of flexible textile material surrounding the mandrel in spaced apart relationship for rotation therewith, means at the side of the mandrel for feeding a strip of fibrous material thereto to cause it to be wound around the textile material by the rotation of the mandrel with the helical coils spaced at a distance apart, means for impregnating the strip with a plastic, toothed wheels adjacent the mandrel engaging between the coils of the strip as they are wound on the mandrel to control the pitch of the winding, and ovens enclosing the mandrel to accelerate the setting of the plastic and render the strip relatively stiff while the coils are maintained in predetermined relationship by the toothed wheels.

23. In an apparatus of the type indicated, a mandrel, means for rotating the mandrel, means for feeding flexible textile material along the mandrel for rotation therewith, means at the side of the mandrel for feeding a strip of fibrous material thereto to cause it to be wound around the textile material by the rotation of the mandrel

22

with the helical coils spaced at a distance apart, means for impregnating the strip with a plastic, a plurality of sets of toothed feed-wheels adjacent the mandrel engaging between the coils of the strip as they are wound around the mandrel to control the pitch of the winding, and a plurality of drying ovens enclosing the mandrel between the sets of feed-wheels.
